UNITED STATES PATENT OFFICE.

FRÉDÉRIC BRICKA, OF MILAN, ITALY.

TEXTILE-FIBER-COMBING MACHINE.

1,408,438.

Specification of Letters Patent.

Patented Mar. 7, 1922.

Application filed July 29, 1920. Serial No. 399,954.

To all whom it may concern:

Be it known that I, FRÉDÉRIC BRICKA, a citizen of the French Republic, residing at Milan, Italy, have invented an Improvement in Textile-Fiber-Combining Machines, of which the following is a specification.

In all combing machines of the Heilmann type, and those derived from it, where a lap held by a nipper is combed by the passage 10 of the needles of rows of combs mounted on the outer or inner surface of a cylinder or of a cone, or on a flat surface in the material projecting beyond the said nipper, the combing line is always situated a few millimetres 15 in front of the nipping line of the said combed lap.

It has been sought to bring the first-mentioned line nearer to the second mentioned line by mechanical means, by using steel 20 blades, or brushes, to press the fibres to be combed into the needles of the last needle bars of the circular comb. But the most careful adjustment of the needles close up to the nipper succeeds only in arriving at a 25 combing line which cannot be overstepped owing to the conical shape of the points of the needles.

The combing action can therefore become operative only from the point where the 30 needle becomes cylindrical.

The more the lap can be divided in gradually smaller slivers by using a greater number of needles to the centimetre, the more efficacious will be the combing operation.

The limit which has been hitherto attainable is about 30 needles to the centimetre, and the steel points become so weak that they stand only with difficulty the work of combing, and are very liable to break and thus 40 perform the combing badly.

The present invention has for its object to present at the instant of the passage of a finishing needle bar, under the closed nipper, a line of needles, having as it were, twice as 45 many points as the needles of the ordinary needle bar, for the purpose of diminishing the free space between the needles, starting at the extreme points of the needles.

In carrying this invention into effect, a 50 movable needle bar is caused to approach a fixed needle bar at an acute angle in such a manner that the points of the needles of the two needle bars will be situated on the same line.

The two needle bars are furnished with 55 equal numbers of needles to the centimetre,

the points of the needles of the movable needle bar come very exactly in the middles of the intervals between and at the same height as the points of the needles of the preceding fixed needle bar which is furnished with for instance 25 needles to the centimetre that are stronger than those having 30 needles to the centimetre, so that instead of 30 needle points, there will be 50 65 needle points which will penetrate the material quite close to the nipping line, and it will be readily perceived that the combing line will have been brought still closer up to the nipping line.

By way of an example of the practical execution of this invention the above stated principle is illustrated in the accompanying drawings as applied to a combing machine of the Heilmann type.

In these drawings:

Figs. 1 and 2 are sections showing two different positions of the parts of the improved combing machine.

Fig. 3 is a plan showing the position of 80 certain operating parts illustrated in Figs. 1 and 2 with relation to the shaft of the combing cylinder.

Figs. 4, 5 and 6 are enlarged views of details.

As shown, the top nipper 1 and the bottom nipper 2 upon which the bottom nipper is closed, present the lap to be combed to the comb segment 4, and the brush 3 fixed to the top nipper brushes the points of the 90 needles in order to facilitate the entry of the material to be combed, into the needle bars.

The movable needle bar 7 is fixed on a support 6 adapted to rock around the axle 5 95 inside the shell of the comb segment 4.

The shaft 10 of the comb cylinder carries two discs 12 to which the comb segment 4 is fixed. A recess in these discs allows the two rollers 9 to pass, one on the right and 100 the other on the left of the support 6.

In Fig. 1, the roller 9 having slidden over the low concentric portion of the fixed cam 11, being pulled by the torsion spring 13, the support 6 with its adjusting screws 14, 105 bears against the inner part of the shell 4 of the segment, and thereby fixes the distance between the needle points *b* and *c* in order that the circular brush may be able to enter thoroughly into the needles and thus 110 clean them easily.

In Fig. 2 the roller 9, being mounted on

the raised portion of the cam 11 fixed to the framing, the movable needle bar 7 has rocked on the axle 5 until its needles *c* present their points at an acute angle at the middles of 5 the intervals between the needles of the fixed needle bar *b* and on the same line as the points of the said needles *b*. The two adjusting screws 8 allow of effecting a micrometric adjustment of this approach.

10 It will be readily perceived that by this arrangement of the parts in accordance with this invention, and as illustrated in Figs. 3 to 6, the lap will be combed twice as much in the position *b c* (Fig. 4) of the needles, 15 as by the bar *a* furnished with the same number of needles.

It is to be understood that any other arrangement may be adopted, such as for instance, an arrangement wherein the movable 20 needle bar *c* is pulled towards the fixed needle bar *b* by the action of a spring, and is moved away by the action of a cam at the instant when the circular brush is passing.

The movable needle bar 7 may also be 25 caused to move in a straight line, without departing from the principle of the invention, according to the type of combing machine to which the said principle is to be applied, for instance where the needle bars are 30 fixed on a flat surface.

Having now particularly described and ascertained the nature of my said invention

and in what manner the same is to be performed, I declare that what I claim is:—

1. In a combing machine of the Heilmann or similar type, the combination with a fixed needle bar, of a movable needle bar having needles which are arranged at an acute angle relatively to the needles of the said fixed needle bar, and staggered so that the points of the needles of the movable needle bar may enter the intervals between the points of the needles of the fixed needle bar, on the line of the said needle points at the instant that the fixed needles enter the lap to be combed, for the purpose of effecting a more intense combing action by reason of the resulting closer arrangement of combing needle points. 35 40 45

2. In a combing machine, the combination with a fixed needle bar, of a movable needle bar co-operating with said fixed needle bar, and means for operating said movable needle bar to cause the needles carried thereby to approach the fixed needles at an acute angle 50 55 at the times when the fixed needles are entering the lap to be combed.

In testimony whereof I affix my signature, in presence of two witnesses.

FRÉDÉRIC BRICKA.
